UNITED STATES PATENT OFFICE.

LOUIS BELL, OF BOSTON, MASSACHUSETTS, ASSIGNOR TO THE GENERAL ELECTRIC COMPANY, OF SAME PLACE.

STARTING ALTERNATING-CURRENT MOTORS.

SPECIFICATION forming part of Letters Patent No. 581,432, dated December 25, 1894.

Original application filed July 3, 1893, Serial No. 479,457. Divided and this application filed March 12, 1894. Serial No. 503,253.
(No model.)

To all whom it may concern:

Be it known that I, LOUIS BELL, a citizen of the United States, residing at Boston, in the county of Suffolk, State of Massachusetts, have invented certain new and useful Improvements in Starting Alternating-Current Motors, of which the following is a specification.

My invention relates to a method and apparatus for starting alternating current motors, and has for its object to so arrange the starting mechanism that such motors shall have considerable torque at starting; to which end I arrange the coils of the secondary of the transformer supplying such motor from any of the ordinary long distance transmission systems so that the coils may be placed in series when the motor starts and afterward may be placed in multiple when the motor attains speed.

This application is a division of my application, Serial No. 479,457, filed July 3, 1893.

As is well known, the starting of alternating current motors presents peculiar difficulty by reason of the fact that not only is the ohmic resistance of the armature conductors considerable, but the high self-induction of these conductors also prevents the passage of any considerable current at starting. It is also well known that for a few moments the armature will stand a potential very much higher than that which is adapted to run it ordinarily, and this fact I take advantage of by the arrangement of the transformer coils just referred to.

The accompanying drawings show diagrammatically illustrations of my invention.

Figure 1 shows the entire system, and Fig. 2 an enlarged view of a switch which I may employ in connection with the transformer.

Referring by letter, G is the generator supplying alternating current to the mains a, b connected to the primary P of the transformer, the secondaries; S, S of which are divided (in the case illustrated) into two parts. The switch H is illustrated herein as a three-pole switch and is provided with contacts 1 to 10.

M is the motor, illustrated as of the induction type, and having shading or short-cir-

cuited coils s, s, &c., as in the patents to 50 Elihu Thomson, Nos. 363,186 and 423,650.

Referring now to Fig. 2, I illustrate on an enlarged scale the switch to which reference has been made. In starting the motor M the switch is thrown to the left and the current 55 passes in series through the two secondaries S, S, as follows: Entering by the line c it passes to contact 2, by the switch arm e to contact 1, through one of the secondary coils S to contact 6, by the switch arm f to contact 5, through the other secondary coil to contact 8, by the switch arm g to contact 10, and out by the line d. To throw the coils in multiple, which is done when the motor has attained its normal speed of running, the switch 65 is thrown to the right and the circuit is as follows: Entering by the line c, it passes to contact 4, by the switch arm e to contact 3, through one of the coils S to contact 6, by cross connection to contact 9, by switch arm f to 70 contact 7, by the cross connection out at line d. The second coil S is connected from the contact 5, making the connection with the line c through contact 4 and the switch arm e, thence through the coils to contact 8, by 75 the switch arm f to contact 7 and thence out by the line d to the motor.

It will be understood that the diagrams which I have given are illustrative merely, and I do not limit myself to a subdivision of 80 the transformer into two coils only, as they may be more or less in number; also the switching mechanism may be of any type necessary, as my invention consists in using the arrangement herein described as a means 85 of starting an alternating current motor, and not in the mere arrangement of the apparatus itself, and this I believe to be distinctly novel and of great utility.

In my application before referred to I show 90 an arrangement of motor coils which will also effect the purposes of my invention. I therefore do not wish to be understood as claiming herein anything shown in that application, but

What I claim is—

1. The method of operating an alternating current motor supplied from a transformer

having a divided secondary coil, which consists in arranging the divided secondary coils in series to start the motor, and changing the relation to multiple when the motor attains speed.

2. In combination, an induction motor, a transformer having a primary coil and a divided secondary coil, and a switch adapted to connect such divided coil in series or in multiple relation to the motor, as set out.

3. A generator of alternating current, lines supplying such current to transformers com-

prising primary windings and divided secondary windings, a switching mechanism adapted to connect such divided secondary windings in series or multiple, and an alternating current motor in circuit with such secondary windings.

In witness whereof I have hereunto set my hand this 10th day of March, 1891.

LOUIS BELL.
